UNITED STATES PATENT OFFICE.

ANDREW PURVES, OF HOLYOKE, MASSACHUSETTS.

METHOD OF PRODUCING WIRE FABRIC.

Application filed May 9, 1922. Serial No. 559,525.

To all whom it may concern:

Be it known that I, ANDREW PURVES, a citizen of the United States, residing at Holyoke, in the county of Hampden and State of Massachusetts, have invented new and useful Improvements in Methods of Producing Wire Fabric, of which the following is a specification.

The present invention relates to a method 10 of producing a woven wire fabric and the product of the same and has for its object more particularly the production of such a fabric with a uniform even selvage of durable character.

15 The invention is especially applicable to the production of the Fourdrinier wire screen employed in paper making machines, and for this purpose is directed to a method which will produce a selvage which is flat 20 and even with the main body of the fabric and one in which the weft wires have not been substantially bruised or distorted during the weaving operation, so that it will wear longer than selvage of Fourdrinier 25 wire as heretofore made. As is well known, a Fourdrinier wire screen should have a flat uniform surface for contact with the rolls of the paper machine, and the greatest difficulty heretofore has been found in the making of 30 such screen with an undistorted selvage.

A Fourdrinier screen is usually woven from small brass wire, both for the warp and weft and with very fine mesh. The brass wire thus used is necessarily soft and individually not of very great strength, so that a very high degree of tension can not be applied to the warp wires. For holding the edge of the fabric straight during the weaving operation and preventing the distortion of the same by the weft wire in 35 passing around the edges of the fabric, attempts have been made heretofore to provide a supplemental support along the edges of the fabric which will receive the strain 40 of the weft in being looped about the edges and thus relieve the main warp wires of the fabric from the distortional effect of said weft wire during this weaving operation.

Such prior methods have usually consisted 50 in employing an edge wire or selvage wire of greater weight and strength than the main warp wires and in having said edge wire held fixed relatively to the main warp wires, with an end portion of the same extending part way within the woven fabric 55 at the selvage thereof so that the weft wire

will be looped at the selvage about this supplemental edge wire, thus protecting the main warp wires at the edge of the fabric from the strain of said weft wire. The 60 tension of the supplemental edge wire thus described has been obtained by allowing the same to drag through a plurality of the weft loops at the selvage during the take-up of the fabric, the number of weft loops at the 65 selvage through which said supplemental edge wire is dragged being greater or smaller, depending upon whether it is desired to increase or diminish the tension on said supplemental edge wire.

The objections to this former practice have been that it is difficult, if not impossible, to properly control the tension of said supplemental edge wire, and moreover, to keep said tension uniform during the 75 weaving of the fabric. This will be obvious from the fact that the weft wire, in being drawn back and forth across the fabric, is not always looped about the edge wire with the same degree of tightness. Such a supplemental edge wire will drag more easily 80 through loose loops than through tight loops of the weft wire, and since the tension and the supporting effect of said edge wire depends upon the drag of its interwoven 85 free end, any uneven tension will produce an uneven selvage.

A further objection to this former method is that the edge wire or drag wire so-called, when tightly embraced by the loops of weft 90 wire will hold back on said loops during the take-up of the fabric, tending to pull or distort the same in the direction of the unwoven part of said fabric. Such a distorting action on the weft wire loops bruises and weakens 95 the same so that the selvage of the fabric when finished, is the weakest part of it and very rapidly deteriorates and breaks in the use of the fabric on the Fourdrinier machine.

Furthermore, in this old method, the edge 100 wire being held stationary with respect to the take-up of the fabric always receives successive blows of the weft wire at substantially the same point, which action rapidly wears it out. If the worn drag wire 105 is not discovered and renewed in time, it will eventually break off in the fabric with damaging results.

In order to overcome the objections to the old practice thus noted, the present invention contemplates the employment at the 110 edge of the fabric during the weaving oper-

ation, of a temporary selvage wire extending throughout the length of the fabric and traveling therewith during the take-up of the same. This continuous selvage wire is of stiffer supporting character than the main warp wires and is also supported and caused to travel with the fabric in such a manner that its tension may be controlled separately from that of the main warp wires, whereby a much greater tension may thus be applied to this supporting selvage wire than exists in the main warp wires. This supporting selvage wire should be of greater strength or weight than the main warp wires so as to withstand the stronger tension imparted thereto, and I have found that a wire of steel of approximately the same size, or perhaps a little larger than the main brass wires, is a suitable wire to use for this purpose. Since such a continuous selvage wire does not drag through the weft loops at the selvage during the weaving operation, it has no distortional or bruising effect upon the same. Furthermore, since its tension does not depend upon a drag action within the fabric, it can be given any tension it requires which tension will remain uniform during the weaving operation.

It is not intended that the continuous selvage wire thus used shall remain in the fabric during its use as a Fourdrinier screen. After the weaving of the fabric is completed, this temporary selvage wire should be removed by pulling the same longitudinally out of the weft selvage loops. In order to facilitate the removal of this continuous selvage wire, a selvage drag wire similar to that previously described in connection with the former practice, is preferably used in conjunction with said continuous selvage wire. Since the selvage drag wire is withdrawn continuously from the selvage during the weaving operation, the finished woven fabric will be provided with vacant weft loops adjacent the continuous selvage wire thereby rendering the withdrawal of the latter an easy matter.

The use of the relatively fixed drag wire in conjunction with the traveling selvage wire also furnishes additional support at the selvage of the fabric for withstanding the strain of the weft wire when thrown back and forth across the fabric. In this case, the tension of the selvage drag wire can also be so adjusted that it will never be sufficient to pull the weft wire loops backwardly and thus distort the selvage, the main support for the weft wire loops being furnished by the continuous selvage wire. In other words, the fixed drag wire need only extend sufficiently into the woven fabric so that it will be easily withdrawn during the take-up of the fabric without straining the weft loops sufficient to distort the selvage of the fabric.

Further features and advantages of the invention will be readily apparent from the following detailed description taken in connection with the accompanying drawings which show preferred means for carrying out the process and in which—

Fig. 1 is a diagrammatic view showing some of the essential elements of an ordinary loom for weaving wire fabric;

Fig. 2 is a detail in plan of one corner portion of such a loom adjacent the let-off end thereof;

Fig. 3 is a side elevation of the mechanism shown in Fig. 2;

Fig. 4 is an enlarged fragmentary detail of a portion of the fabric as it appears during its process of being woven in the loom;

Fig. 5 is an enlarged detail in perspective of a portion of the finished fabric in an attempt to show the appearance of the finished selvage thereof; and

Fig. 6 is an enlarged detail in cross-section of a portion of said finished fabric.

Referring more particularly to the drawings—

The process may be carried out on the usual type of a wire weaving loom in which 1 indicates the warp beam or let-off roll, 2 the whip roll, 3 the usual lease strips, 4 the heddle frames, 5 the beat-up reed, 6 the breast roll, and 7 the take-up or cloth roll. The main warp wires of the fabric are indicated at 8 and are supported in the heddle frames, for the forming of the successive sheds therewith in a manner well understood. The weft wire is indicated at 9.

At each edge of the selvage of the fabric to be woven, suitable means are arranged to carry the temporary selvage wires previously described. The selvage drag wire indicated at 10 may be suitably mounted by having one end fastened to a coiled spring 11 which in turn may be secured to any stationary part of the loom, as for instance the lease strips 3 as shown, so that said drag wire 10 is adapted to be held fixed relative to the main warp wires 8 during the take-up of the fabric. As shown in Fig. 4, the drag wire 10 is arranged to extend part way within the woven fabric, and due to its fixed fastening, to be continuously withdrawn from the same during the take-up of the fabric. This fixed drag wire should not extend far enough into the fabric being woven to produce any substantial friction in being withdrawn during the take-up of the fabric, or at least, not enough friction to cause a strain on the weft loops which would distort the selvage of the fabric.

The traveling or temporary selvage wire indicated at 12 is preferably located outside of the drag wire 10 and is arranged to extend throughout the length of the fabric and to travel therewith during the take-up of the same. This traveling selvage wire 12 is

- preferably let-off from an independent spool or reel such as 13 separate from the let-off roll of the main warp wires, so that the let-off tension of said wire 12 may be separately controlled from the tension of the main warp wires 8. Any suitable tensioning means may be employed in connection with the let-off reel 13 for adjusting and controlling the tension on the same, and as typical of such means, I have shown a strap brake 14 wound partially around the hub of said reel 13 and adapted to be adjusted for different degrees of braking action by means of a screw-threaded bolt 15 passing through a lug 16 of said loom frame and having secured thereto adjusting and lock nuts 17. As before stated, the traveling wire 12 is carried throughout the length of the fabric and is wound up therewith on the take-up roll. The selvage wire 12 is herein referred to as a temporary wire for the reason that it is not intended that the same shall remain in the woven fabric during the use of the latter as a Fourdrinier screen.
- 25 The drag wire 10 and the traveling selvage wire 12 are preferably carried through separate heddle frames of the loom so as to have successive sheds formed therebetween for the passage therethrough of the weft wire 9 in its movement back and forth across the fabric, whereby said wires 10 and 12 are interwoven with the fabric at the selvage thereof, as shown in the upper part of Fig. 4. It has been found that by carrying the 35 two selvage wires 10 and 12 in oppositely moving heddle frames, the effect of raising and lowering one selvage wire will be balanced by the opposed movement of the other selvage wire during the shed forming action, and thus eliminate the wavy effect at the selvage of the fabric which would be caused by the employment of only a single selvage wire.
- The weft wire 9 is looped at each edge of 45 the fabric about the outside selvage wire 12, and since this selvage wire 12 travels with the fabric during its take-up, there is no action tending to pull back and distort said weft wire loops during the weaving operation. The continuous take-up of the fabric causes the drag wire 10 to be continuously withdrawn from the selvage as shown in the lower part of Fig. 9, leaving the fabric as it 50 is finally woven with a series of vacant weft loops at the inside of the adjacent or continuous selvage wire 12.
- After the fabric is thus completely woven, weft wire 12 is pulled out by hand or other suitable means. When the selvage wire 12 55 is finally removed from the fabric, the selvage will be in the condition shown in Figs. 5 and 6, in which double loops of the weft wires are left vacant by the withdrawal of both of said selvage wires 10 and 12. This 60 will be the condition of the fabric as it is to be used on the paper making machine. It should be particularly noted that the vacant weft loops thus formed at the outside edge of the finished fabric are not subjected to strain by the removal of the temporary 70 selvage wires sufficient to distort the selvage of the fabric, which results in the production of a wire fabric for Fourdrinier use having an even, flat, and substantially smooth selvage.
- 75 What I claim is:
1. The method of producing a woven wire fabric which consists, in employing at the edge of the fabric to be woven a temporary selvage wire traveling therewith during the 80 take-up of the fabric in the weaving operation, looping the weft wire around said selvage wire during the weaving operation, forming a row of vacant loops of said weft wire adjacent said edge warp wire during the weaving and take-up of the fabric to facilitate the final removal of said warp wire, and finally when said fabric is woven removing said selvage wire.
  2. The method of producing a woven wire 90 fabric which consists, in employing at the edge of the fabric to be woven a temporary selvage wire of stiffer supporting character than the main warp wires of said fabric and traveling therewith during the take-up of the fabric in the weaving operation, looping the weft wire around said selvage wire during the weaving operation, and finally when said fabric is woven removing said selvage 95 wire.
  3. The method of producing a woven wire fabric which consists, in employing at the edge of the fabric to be woven a temporary selvage wire traveling therewith during the take-up of the fabric in the weaving operation, looping the weft wire around said selvage wire during the weaving operation, controlling the tension of said selvage wire independently of the main warp wires during the weaving operation, and finally when said fabric is woven, removing said selvage 100 wire.
  4. The method of producing a woven wire fabric which consists, in employing at the edge of the fabric to be woven a temporary 105 selvage wire traveling therewith during the take-up of the fabric in the weaving operation, looping the weft wire around said selvage wire during the weaving operation, applying a greater tension to said selvage wire than to the main warp wires during the weaving operation, and finally when said fabric is woven, removing said selvage wire.
  5. The method of producing a woven wire fabric which consists, in employing at the same edge of the fabric to be woven two temporary selvage wires, the outside 120 selvage wires extending throughout the length of the fabric and traveling therewith during the take-up of the same in the 125
- 130

weaving operation, the inside selvage wire extending only part way into the woven fabric and relatively fixed so as to be continuously withdrawn from the fabric during the weaving operation.

6. The method of producing a woven wire fabric which consists, in employing at the same edge of the fabric to be woven two temporary selvage wires, one of said 10 selvage wires extending throughout the length of the fabric and traveling therewith during the take-up of the same in the weaving operation, the other selvage wire extending only part way into the woven 15 fabric and relatively fixed so as to be continuously withdrawn from the fabric during the weaving operation, and finally when said fabric is woven, removing said first named selvage wire.
- 20 7. The method of producing a woven wire fabric which consists, in employing at the same edge of the fabric to be woven two temporary selvage wires, the outside selvage wire being of stiffer supporting 25 character than the main warp wires of said fabric and extending throughout the length of the fabric and traveling therewith during the take-up of the same in the weaving operation, the inside selvage wire extending 30 only part way into said woven fabric and being relatively fixed so as to be continuously withdrawn from the fabric during the weaving operation, and finally when said 35 fabric is woven, removing said outside selvage wire.

8. The method of producing a woven wire fabric which consists, in employing at the same edge of the fabric to be woven two temporary selvage wires, the outside 40 selvage wire extending throughout the length of the fabric and traveling therewith during the take-up of the same in the weaving operation, the inside selvage wire extending only part way into said woven 45 fabric and being relatively fixed so as to be continuously withdrawn from the fabric during the weaving operation, controlling the tension of said outside selvage wire independently of the main warp wires during 50 the weaving operation, and finally when said fabric is woven, removing said outside selvage wire.

9. The method of producing a woven wire fabric which consists, in employing at the same edge of the fabric to be woven 55 two temporary selvage wires, the outside selvage wire being of stiffer supporting character than the main wires of said fabric and extending throughout the length of the 60 fabric and traveling therewith during the take-up of the same in the weaving operation, the inside selvage wire extending only part way into said woven fabric and being relatively fixed so as to be continuously 65 withdrawn from the fabric during the

weaving operation, applying greater tension to said outside selvage wire than to the main warp wires of said fabric during the weaving operation, and finally when said fabric is woven removing said outside selvage wire. 70

10. The method of producing a woven wire fabric which consists, in employing at the same edge of the fabric to be woven two temporary selvage wires of stiffer supporting character than the main warp wires of said fabric forming successive sheds with said selvage wires for the interweaving therewith of the weft wire during the weaving operation, looping the weft wire around 80 the outside selvage wire, both of said selvage wires being removed from the woven fabric after being interwoven therewith.

11. The method of producing a woven wire fabric which consists, in incorporating 85 into the same edge of the fabric during the weaving operation two temporary selvage wires one of said selvage wires traveling with the fabric during the take-up of the same in the weaving operation, the other selvage wire being relatively fixed so as to be continuously withdrawn from the fabric during the weaving operation, and finally when said fabric is woven removing 90 said first named selvage wire. 95

12. The method of producing a woven wire fabric which consists, in employing at the same edge of the fabric to be woven two temporary selvage wires, forming successive sheds with both of said selvage wires 100 for the interweaving therewith of the weft wire during the weaving operation, looping the weft wire around the outside selvage wire, causing said outside selvage wire to travel with the fabric during the take-up 105 of the same in the weaving operation, holding the inside selvage wire relatively fixed so as to be continuously withdrawn from the fabric during the weaving operation, and finally when said fabric is woven removing 110 said outside selvage wire.

13. The method of producing a woven wire fabric which consists, in employing at the same edge of the fabric to be woven two temporary selvage wires, carrying the 115 weft wire in between said selvage wires and around said outside selvage wire during the weaving operation, holding said inside selvage wire relatively fixed during the weaving operation of the fabric so as to be continuously withdrawn from the fabric by the take-up movement of the same, carrying the outside selvage wire with the fabric during this take-up movement, and finally when said fabric is woven removing 120 125 said outside selvage wire.

In testimony whereof I have affixed my signature.

ANDREW PURVES.
